FLUSH TANK INLET CONTROL VALVE

Louis Sirotek, Chicago, Ill.

Application March 19, 1956, Serial No. 572,248

3 Claims. (Cl. 137—244)

This invention relates to improvements in water inlet control valves such as are used in toilet flush tanks and particularly, is an improvement of the valve construction described and claimed in my United States Letters Patent No. 2,730,120 issued January 10, 1956.

An important object of my invention is to provide a flow control valve whose construction is such that it can be quickly and easily assembled and secured, and when desired, rapidly and readily disassembled to provide access to the interior and to the components thereof.

Another object of the invention is to provide a control valve wherein water flow thereinto may be supplied from its bottom or top and which, in usage, will positively prevent undesirable back siphonage of water therethrough into the conventional water supply pipe to which the same is connected.

It is also an object of the invention to provide a valve of the stated character which, during that period when it is open and admitting water to a tank equipped therewith, will be assured of remaining in a fully open position until such time as the level of the water flowed therethrough into said tank reaches a predetermined and proper point, whereupon the valve is actuated automatically to an instantly effected and completely closed position and similarly shuts off the flow of water therethrough into the tank. Thereby, a faster filling of the tank is accomplished; moreover, because the cut-off action of the valve is immediate, water whistling as it flows through the gradually closing present type of control valve is eliminated entirely.

A further object of my invention is to provide a control valve so constructed that, by simple and convenient adjustment, it can be regulated to admit and pass a pre-selected increased or decreased volume of water.

Yet another object of the invention is to provide a flush tank inlet control valve whose operation during the discharge of water therefrom into the tank will be noiseless and without objectionable cascading and/or swirling effects, and whose operation in the cutting off of the flow of water therethrough into said tank will likewise be noiseless.

A still further object of the invention resides in providing to the valve a novel and operationally positive means for maintaining the valve chamber pressure escape port constantly open and free of passageway clogging matters.

The foregoing, as well as other objects, advantages and meritorious teachings of my invention will be in part obvious and in part pointed out in the following detailed disclosure thereof, when taken in conjunction with the accompanying drawings, it being understood that the forms of the invention presented herein are precise and what are now considered to be the best modes of embodying its principles, but that other modifications and changes may be made in specific embodiments without departing from its essential features.

In the drawings:

Figure 1 is a vertical and medial section through my

2

improved control valve construction with its operating parts shown in closed position.

Figure 2 is a horizontal section taken on the line 2—2 of Figure 1, looking in the direction in which the arrows point.

Figure 3 is a fragmentary vertical and medial section through the valve, wherein its operating parts are shown in open position whereby to admit of the flow of water thereto and therefrom.

10 Figure 4 is a vertical and medial section through a modified form of my improved control valve in which water inflow thereto is effected from its top rather than from its bottom, as is shown in Figure 1, and wherein the assembled valve construction is pendently supported instead of being column supported, as in said Figure 1, and,

15 Figure 5 is a horizontal section taken on the line 5—5 of Figure 4, looking in the direction in which the arrows point.

20 Referring in detail to the accompanying drawings and particularly, to the Figures 1—3 thereof, my improved control valve consists of a frusto-conically shaped and chambered housing 1. The top and bottom of the housing are open and plane. It is divided, intermediately of its top and bottom ends, by a horizontal or transverse wall 2 having a substantially concentrically located opening therethrough. Thus, an upper chamber 3 and a lower chamber 4 are provided to and within the same.

25 A head 5, corresponding in shape and size to the plane open upper end of the housing 1, is received thereon. Said head is formed with a concentrically located and screw-threaded opening from which co-axially disposed upper and lower screw-threaded nipples 5a extend. Also, the head is formed with radially disposed and relatively spaced ribs 6.

30 Each of the ribs 6 has a duct 7 in and throughout their lengths opening onto the outer ends thereof and into said concentrically located opening. Plugs or stopples 8 are threaded into the outer ends of the ducts and 35 obviously, are removable therefrom, if desired or required. Also, each of these ducts are formed with downwardly and outwardly discharging water outlet ways or ports 9; it being noted that said outlet ways open onto the normally lower side of the head 2 inwardly of the plugs 8 and that bosses 10 are formed on the head thereabout.

35 Other and relatively spaced outlet ways or ports 10 are formed in those portions of the head between the ribs 6, as is shown in Figure 2 of the drawings. These 40 particular ports, it will be noted, open onto the lower and upper sides of the head 5.

45 The outer perimeter of the head 5 is formed or otherwise provided with a fixed and downwardly disposed lip 11 whose surface is plane and matches substantially, with 50 that of the housing open upper end. Interposed between the plane surfaces of the housing open upper end and the lip 11 of the head 5 is a diaphragm 12 made of rubber or a suitable flexible composition. It is of shape and size that its outer margins lie substantially flush with 55 the adjacent outer side portions of said lip and housing. An opening or way of shape and size similar to the opening in the head 5 is formed in this diaphragm and registers with the latter opening. To improve the flexibility of the diaphragm, I may and preferably do weaken 60 the same by scoring as at 13, or in any other suitable manner.

65 Extending longitudinally or vertically through the housing 1 and head 5 to points above and below the same is an externally screw-threaded pipe or tube 14. The diameter of this pipe is such that it is rather snugly engaged through the casing open lower end, the opening in the wall 2, and snugly engaged through the opening in the diaphragm

12. It's upper end is threadedly engaged in and through the opening in the head 5 and its nipple 5^a.

Relatively vertically spaced series of ports 15 are formed in and about the tube 14 and communicate with the housing chamber 4, while a perforate disk or strainer 15' is fixedly received within said tube between the spaced series of ports 15 (see Figure 1). A screen strainer 16 is supported from the lower side of the wall 2 and envelops that portion of the pipe having the uppermost series of ports 15 therein.

To connect the pipe 14 to the housing 1, an internally screw-threaded lock sleeve 17 is engaged over that portion of said pipe within the housing chamber 3 and is turned into binding bearing engagement with an adjacent portion of the housing wall 2, having a sealing gasket 18 interposed therebetween for an obvious purpose.

The lower and extended end portion of the pipe 14 threadedly receives a flanged coupling sleeve 19, its flanged end being in fluid tight contact with the plane lower open end of the housing and sealed by a gasket 20, while its lower portion is turned onto the screw-threaded adjacent end portion of a conventional water supply or stand pipe 21.

As above stated, the pipe 14 extends through the head 5. Its upper end portion is internally screw-threaded. A valve 22 is rotatably and threadedly engaged in the internally threaded upper end portion of the pipe 14 and has crossed and diametrically disposed ports 23 formed in and over its inner end so positioned that they may be selectively aligned, partially aligned or disaligned with the ways 24 in the pipe 14. These ways 24 register with the open ends of the ducts 7 in the ribs 6, as shown in Figure 1 of the drawings. The head 22' is preferably peripherally knurled and has index markings 24', corresponding to the arrangement or dispositioning of the ports 23, inscribed in or otherwise provided to its exposed side, for an obvious purpose.

A sealing gasket 25 is interposed between the valve head 22' and the adjacent end of the pipe 14.

To effect dispersed discharge flow of water from the housing 1 via the head 5 a cap 26 of shape and size such that it will cappingly and snugly engage over the head and the diaphragm, is provided (see Figure 1). An opening is formed in and concentrically of the cap permitting its engagement over the upper head nipple 5^a and bearing engagement on the head. Perforations 26' are formed in the top side of the cap and overlie the head 5, while an opening is formed in a portion of its peripheral flange to permit the snug engagement of a refill tube 27, hereinafter more fully described, therein.

A downwardly flanged water flow deflecting cap 28 having a concentric and screw-threaded way therethrough is turned into engagement with the upper threaded nipple 5^a and cappingly overlies the perforate top and portions of the dispersing cap 26 in spaced relation thereto. Thus, an outwardly and downwardly disposed water channel or discharge way is effected between the two caps 26 and 28 openings onto the upper portions of the walls of the housing 1. Obviously, by turning the deflecting cap clockwise or counter-clockwise, the depth of the above noted water channel may be selectively varied if desired or required.

The refill tube 27, as will be understood, serves to provide water refill to a toilet bowl communicating therewith whereby to provide the usual sewer gas seal therein. That the tube may have water fed thereto, a way 27' is formed in and through a portion of the head 5 and communicates with its adjacent open end.

Positioned on one side of the housing 1 and opening into its chamber 3 is a valve cylinder 29. A seat is formed in the same at its point of communication with said chamber 3, while a duct 30 is formed therein inwardly of and adjacent said seat and at an angle to its longitudinal axis, communicating with a discharge port 30' opening outwardly onto the cylinder.

A valve 31, having a packing equipped stem 32 extending into and through the cylinder, is seatable on the valve cylinder seat. The outer and free end of the stem is pivotally connected at 33, to an intermediate portion of a lever 34 mounted on a bracket arm 35 carried by the cylinder 29. The upper side of the bracket arm carries a fixed loop 36 receiving and firmly supporting the refill tube 27 in relation to the housing 1.

The lower and free end of the lever 34 has the adjacent end of a conventional form of float carrying arm 37 threadedly engaged therethrough, as at 38.

To impart movement retarding drag to the arm 37 whereby movement of the valve 31 to its closed position on the cylinder seat will be abruptly and wholly effected only at a predetermined point of upward travel of said arm, a spring arm 39, having a curved intermediate portion, is connected at one end, at 40, to the lever free end. Its remaining end is disposed beneath and in proximity to the inner end of the cylinder 29 and fixedly carries a bearing pin 41 arranged adjacent and moveable onto a cam or boss 42 on said cylinder. In the open position of the valve 31, the pin 41 is disposed at the base of the cam, as shown in Figure 3. However, as the water level in an equipped tank (not shown) rises, upward rise and travel of the float carrying arm 37 is resisted to a predetermined pressure point. When such point is reached, the pin 41 on the spring arm 39 will abruptly ride onto the cam 42 (see Figure 1). In so doing, the valve 31 will immediately and abruptly move into full seating and closed position with relation to the open inner end of the cylinder 29 (see Figure 1) discontinuing the outflow of water from the housing chamber 3 through the duct 30 and port 30'.

A water by-pass or bleeding sleeved port 43 is provided to the housing horizontal wall 2 and as will be understood, effects communication between the housing chambers 4 and 3.

Discharge ways 43' are formed in the sleeve. Thus, water flowed into the chamber 4 from the pipe 14 will rise through said sleeved port and flow into the chamber 3. To prevent clogging of the sleeved port with foreign matter which might interrupt the chamber intercommunication, a passageway cleaning pin 44 is loosely and movably received therein, being headed at 44' to ensure its retention.

In operation of the hereinbefore described form of my invention and assuming that a flush tank equipped therewith has been emptied of water by a flushing operation and is needy of refilling, the float carrying arm 37 will have moved downwardly to the position shown in Figure 3 of the accompanying drawings. Thus, the lever 34 will have been swung inwardly toward the valve housing 1, moving the stemmed valve 31 from its seat in the valve cylinder 29. When this valve is opened, water within the housing chamber 3 will be discharged therefrom via the duct 30 and port 30' in said cylinder. With the outflow of water from the housing chamber 3, as above, upward thrust and/or water pressure on the diaphragm 12 will be discontinued. In consequence, said diaphragm will be free to flex and move downwardly away from the ports 9 communicating with the ducts 7 in the ribs 6. Thereupon, water in the pipe 14 will flow therefrom. A portion of such flow will be from the ports 15 into the lower chamber 4 of the housing 1. Other flow will be effected from the upper end of said pipe via the valved ways 24 therein into and through the ducts 7 of the head ribs 6. This water flow will continue through the aforesaid ports 9 into downwardly thrusting engagement with the diaphragm 12, moving it downwardly to the open position illustrated in Figure 3. Continuing its flow, the water will pass upwardly through the ports 10' in the head 5 and outwardly through the perforations 26' in the cap 26. From here, the water will discharge outwardly and downwardly by the deflecting cap 28 over the surfaces of the housing 1 into the equipped flush tank. At this point, it

will be noted that because of the downward flowing of the water over the housing walls, its cascading, splash and swirling will be eliminated as will that noise incident to such conditions. Thus, the equipped flush tank will be refilled to the desired level without that objectionable noise common to the refilling of heretofore used types of flush tanks and valves.

Concurrently with the outflowing of water from the upper end of the control valve, as just described, the water discharged into the housing chamber 4 will rise therein and overflow through the by-pass or bleeding sleeved port 43 into the chamber 3 from where it will pass by the now open valve 31 into and from the cylinder 29 through the duct 30 and port 30'. Hence, the flow of water into the flush tank for effecting its refilling will be augmented.

As the level of water discharged from the control valve into the flush tank rises, so too will the float (not shown) carried by the pivotally mounted arm 37. Due to the provision of the spring 39 and bearing pin 41 to the said arm, and its cooperation with the cam 42, the rate of speed of the rise of the arm will be retarded until a substantially predetermined pressure thereto or thereon has been reached. At this time, the pin 41 rides abruptly onto the cam 42 to the position shown in Figure 1 of the drawings, whereupon the float carrying arm will rise sharply and in so doing, will move the valve 31 of the cylinder 29 abruptly and sharply to its fully closed position (see Figure 1).

The outflow of water from the chamber 3 being thus discontinued, its level will rise therein and at a substantially predetermined point of rise, will impart pressure and upward thrust to the underside of the diaphragm 12. This continuing pressure and upward thrust will flex said diaphragm upwardly, causing it to engage over and close the ports 9 communicating with the ducts 7 of the head ribs 6. Thereby, the flow and the discharge of water from the control valve into the aforesaid flush tank will be discontinued and said tank will have been refilled with water to the required level.

Concurrently with the filling of the flush tank, as above noted, a limited flow of water from the ducts 7 of the head 5 will be effected through the way 27' in said head and flowed into and through the refill tube 27 discharging, at its outer end into a toilet bowl, thereby effecting the usual water seal in said bowl to preclude passage of gases thereby. Of course, as and when the diaphragm 12 closes the ports 9 in the above described manner, the flow of water to the refill tube 27 will be discontinued.

The flow of water through the ducts 7 of the head ribs 6 from the pipe 14 can be selectively regulated by turning adjustment of the valve 22 which, in turn, will vary the extent of registration of its ports 23 with the ways 24 in the pipe.

It should also be noted that the pin 44 which is movably or reciprocally received by and in the sleeved port 43 will function to maintain a clear and unclogged passage therethrough, in that it will be pushed or thrust upwardly by the constant water pressure in the chamber 4, when pressure in the chamber 3 is released. Thus, said pin will rise to the underside of the diaphragm 12 and when this diaphragm is flexed downwardly, its underside will contact and thrust the pin 44 downwardly through the sleeved port 43. Also, when the pressure is equalized in the chambers 4 and 3, as when the control valve is in its closed position, the pin 44 will move or slide downwardly through the sleeved port by gravity and its own weight. Consequently, intercommunication between the housing chambers 3 and 4 is constantly and effectually maintained.

Water entering the flush tank equipped with my improved control valve discharges over the top of said valve and downwardly over the valve body. Because the improved valve is supported by the water supply stand pipe 21 above the normal or maximum water level in said tank, it will be understood and appreciated that this arrange-

ment and construction will function to positively prevent undesirable back siphonage of water therethrough into said stand pipe 21 and into the water supply pipe below the tank. Therefore, it follows that the hazard of water pollution will be eliminated, this, because as and when a water column within the stand pipe 21 lowers or recedes and creates a suction within and through the pipe or tube 14 and through the improved control valve, said valve being supported in air, to wit, above and beyond the flush tank contained water, will not permit spillage or return of flush tank water therethrough and hence into the stand pipe 21.

The assembly of my improved control valve is of material importance and value. Its components may be quickly and conveniently assembled and securely interconnected by engagement of the pipe 14 therethrough in the manner hereinbefore described. And in such assembly, the diaphragm 12, head 5, dispersion cap 26 and deflecting cap 28 will be effectually held or retained in their respective relationships. By the same token, the construction may be quickly and conveniently disassembled to provide access for parts adjustment, inspection, repair or replacement, as required.

In the Figures 4 and 5 of the accompanying drawings, I have shown a slightly modified form of my improved valve. In its modified form, the control valve embodies (1) a different type of support, (2) a different arrangement of the sleeved port and the cleaning pin, (3) a different arrangement of chambers within the valve housing, and (4) a different coursing or inflowing of water thereto. By this modified form of my invention, a somewhat simplified construction is provided and also, due to the elimination of the stand pipe 21 of the form of the invention shown in Figures 1, 2 and 3, any and all possible back siphonage into the water supply pipe and its resultant pollution will be eliminated.

In said modified form of the invention, a substantially frusto-conical housing 1' is provided, the same being divided into chambers 3' and 4' by a partition wall 2'. The opposite ends of the housing are open and plane. The partition wall 2' is provided with a concentrically located opening.

A diaphragm 12' made of rubber or other suitable flexible composition is received on the upper open and plane end of the housing 1'. A head 5' formed or otherwise provided with a plurality of radially disposed ribs 6' having ducts 7' formed in and extending therethrough is received on the upper and outer side of the diaphragm 12'. The outer ends of the ducts 7' are closed by plugs or stopples 8' while the inner ends of said ducts open onto an opening in and concentrically of said head. The outer end portions of the ducts 7' are each provided with downwardly and outwardly discharging water outlets or ports 9'.

A perforate cap 26a having a concentrically located and larger opening therethrough is cappingly and snugly engaged over the head and the diaphragm.

To deflect the outward flow of water through the perforate cap 26a and direct the same downwardly and over the outer surfaces of the control valve housing 1', a downwardly flanged water flow deflecting cap 28' having a concentric and screw-threaded way therethrough is turned into engagement with a water inlet fitting 45, hereinafter more fully described. By turning the deflecting cap clockwise or counter-clockwise, the depth of the channel or way between it and the perforate cap 26a may be selectively varied.

Fixedly mounted or positioned on one side of the housing 1' and opening into its chamber 3' is a valve cylinder 29' having a seat formed in or on that portion of the same communicating with said chamber. Also, a duct 30a is formed in a portion of the cylinder wall inwardly of and adjacent said seat, being disposed at an angle to its longitudinal axis and communicating with a discharge

port 30^b in the cylinder wall and opening outwardly thereonto.

A valve 31' carrying a suitably packed stem 32' is received by the cylinder 29' and is seatable on the above described cylinder valve seat. The outer and free end of the stem 32' is pivotally connected, at 33' to an intermediate portion of a lever 34' mounted on a bracket arm 35' carried by the cylinder 29'. A loop 36' is carried on the upper end of the bracket arm for a purpose which will be presently described.

The lower and free end of the lever 34' is connected to a conventional form of float carrying arm 37', as at 38'.

To retard upward pivotal movement of the float carrying arm 37' as and when a flush tank equipped with my improved valve is being filled with water, a construction embracing a spring arm 39', a bearing pin 41' and a cam 42' on an adjacent portion of the underside of the cylinder 29' is provided, the same corresponding to a similar construction more specifically described in the form of my invention shown in Figures 1, 2 and 3.

A refill tube 27^a is extended through the loop 36' on the lever 34' into communication with the head 5' via a way 27^b in the latter.

A water supplying and assembly interconnecting pipe 14', externally screw-threaded throughout its length, is extended longitudinally and/or vertically through the housing 1', diaphragm 12', head 5', cap 26^a and deflecting cap 28' to a point above the latter. A lock nut 46 is threadedly engaged with the lower end of the pipe and seats on and closes the open plane lower end of the housing 1'.

The upper portion of the pipe 14' has a plurality of relatively spaced and radially disposed ports 47 formed therein which, with proper positioning of the pipe, will align with the open inner ends of the ducts 7' in the head ribs 6', it being noted that said pipe 14' is threadedly engaged through the concentric opening in the head 5'.

The upper end of the pipe 14' is provided with a second series of relatively spaced and radially disposed ports 48. These ports have communication with the water inlet fitting 45. To control and/or regulate the volume or extent of flow of water into the pipe 14' from the fitting 45, a ported cylindrical rotatable valve 49 is threadedly engaged with the extended upper end of said pipe 14'. The ports therein, with rotation of the valve, may be selectively aligned, partially aligned or disaligned with the pipe ports 48. Preferably, the cylindrical valve 49 is provided with a head 49' having its periphery knurled and its upper and outer side inscribed with suitable index markings whereby to facilitate a desired adjustment of the valve with relation to the pipe ports 48. Also, a gasket 50, or its equivalent, is interposed between the head 49' and adjacent portions of the fitting 45 for an obvious purpose.

The water inlet fitting 45 consists of a hollow annular head, open at its top, and communicating with a nipple-like extension 51 having an internally screw-threaded socket fixture 52 thereon. The fixture, obviously, permits connection to a usual water supply pipe (not shown) in order that water may be provided to and flowed into the control valve; also, as a means for supportingly connecting said control valve to the stand pipe within an equipped flush tank well above its maximum water level.

In order that communication will be established between the housing chamber 3' and the pipe 14', a partition or wall 53 is fixedly mounted within said pipe, separating its upper portion from its lower portion. A horizontal way 54 is formed in the partition and communicates with a port 55 in an adjacent portion of the pipe 14'.

To maintain unobstructed communication between the pipe 14' and the housing chamber 3', a passageway cleaning pin 44' is loosely and slideably received in the ways 54-55, having its outer end headed, as at 56 and positioned adjacent and normally in contact with the valve 31'. Thus, as the valve 31' is moved away from

its seat in the cylinder 29', the pin 44' will be moved through the sleeved port and as the valve 31' moves into its closed position, the water pressure in the pipe 14' will push or thrust the pin back into contact with the adjacent end of the closed valve 31', thereby assuring sufficient sliding movement of the same to maintain a clear and uninterrupted water way through the port, i. e., prevent its fouling or clogging.

Water is prevented from entering the housing chamber 10 4' from its chamber 3' by arranging a sealing gasket 57 about the pipe 14' and on adjacent portions of the horizontal wall 2'; a lock nut 58 being threadedly engaged about and adjacent an intermediate portion of the pipe and bearing on the gasket, as clearly shown in Figure 4 15 of the drawings. An opening 58' is formed in an appropriate portion of this lock nut in registering relation to the port 55 for an obvious purpose.

From the foregoing, it will be understood that the pipe 14' when positioned and engaged with the control valve construction in the aforesaid manner, will serve to securely interconnect its component parts, retaining them in assembled and operative relationships. Moreover, should it be required, access may be conveniently and quickly had to said component parts, by removing the pipe 20 from its interconnected relationship thereto.

In operation of the modified form of my invention as disclosed in the Figures 4 and 5, flush tank filling water enters the control valve by way of the water inlet fitting 45, flowing through the valve adjusted or regulated ports 48 into and downwardly of the pipe 14'. A portion of this water flows through the ways 54-55 into the housing chamber 3'. The remainder of the flow is effected from the pipe 14' through the ducts 7' of the head ribs 6'. Thus, with emptying of water from the equipped flush tank, as in a flushing operation, the float carrying arm 37' will have been moved downwardly to its lowest point of pivotal travel. In so doing, the valve 31' will be moved away from its seat on the cylinder 29'. Consequently, water within the chamber 3' will be outletted therefrom through the duct 30^a and the way 30^b in said cylinder 29', removing pressure from the flexible diaphragm 12'. Concurrently, water flowing from the pipe 14' through the ducts 7' of the head ribs 6' will flex the diaphragm downwardly away from the ports 9'. Thereby, water will be flowed through said ports 9' and thence upwardly through ports formed in the head 5', corresponding to those indicated by the numeral 10' in the Figures 1-3 of the accompanying drawings. Water flowing through these last mentioned ports is outletted through the perforate dispersing cap 26^a and is discharged over the deflecting cap 28' downwardly and along the outer surface of the housing 1' into the equipped flush tank.

As and when the required amount of water has been discharged into the equipped flush tank and the required level has been attained therein, the float carrying arm 37' will have been raised to its uppermost pivotal position. In so doing the lever 34' will have swung outwardly from the housing 1' and will have moved the valve 31' into its seated and closed position on the valve seat of the cylinder 29'. Thereupon, a continuing flow of water through and from the pipe 14' into the housing chamber 3' will fill said chamber and will exert an upward pressure or thrust on the gasket 12', hence, move the same onto and over the ports 9' of the ducts 7' and discontinue the discharge of water from the control valve into said flush tank.

To prevent entry of foreign matters from the water inlet fitting 45 into the valve construction, it is preferable that a cylindrical screen 59 be set into said fitting in a manner to surround or envelop the ports 48 in the pipe 14 and those in the rotatable valve 49. Thus, all water entering through said fitting passes first through the screen or strainer. In consequence, the entry of foreign matter into the valve construction which may tend to or clog

the same and reduce its operating efficiencies will be positively prevented.

I claim:

1. A water inlet control valve, comprising a housing partitioned into lower and upper chambers, said chambers intercommunicating by way of a port in the partition, a cleaning pin received by and movable in said port, a discharge head on the housing above the upper chamber having ducts in the same opening only onto its lower side and communicating with an opening in an intermediate portion thereof and having ways therein opening onto its lower and upper sides, a diaphragm between the head and the housing upper chamber engageable, at times, over and closing the head lower side opening ducts, and a pipe engaged through and connected to said housing, diaphragm and head retaining the same in assembled relation and communicating with the housing lower chamber and the ducts and ways in the head.

2. A water inlet control valve, comprising a housing partitioned into lower and upper chambers, a water bypassing sleeve in the upper chamber supported by the partition communicating with the lower and upper chambers, a water inflow operated cleaning pin movably received within and through said sleeve, a discharge head on the housing above the upper chamber communicating therewith, water pressure actuated means between the head and the upper chamber whereby to control communication between said head and upper chamber, water outlet control means communicating with the upper

chamber, and a water inflow pipe extended through the housing, discharge head water pressure actuated means and connected to said housing and head and communicating with the discharge head and lower chamber.

- 5 3. A water inlet control valve, comprising a housing partitioned into lower and upper chambers, a water bypassing sleeve in the upper chamber supported by the partition communicating with the lower and upper chambers, a water inflow operated cleaning pin movably received within and through said sleeve, a discharge head on the housing above the upper chamber communicating therewith, water pressure actuated means between the head and the upper chamber whereby to control communication between said head and upper chamber, water outlet control 10 means communicating with the upper chamber, a water inflow pipe extended through the housing, discharge head and water pressure actuated means connected to the housing and the discharge head, said inflow pipe having relatively longitudinally spaced ports therein adjacent and 15 communicating with the housing lower chamber, and screening means in said lower chamber engaged about and over the uppermost of the ports in said inflow pipe.
